UNITED STATES PATENT OFFICE.

DAVID CARTER, OF STIRCHLEY, ENGLAND.

VALVE FOR ROTARY ENGINES.

SPECIFICATION forming part of Letters Patent No. 654,227, dated July 24, 1900.

Application filed March 6, 1900. Serial No. 7,804. (No model.)

To all whom it may concern:

Be it known that I, DAVID CARTER, engineer, a subject of the Queen of Great Britain, residing at 6 Ashtree road, Stirchley, near 5 Birmingham, England, have invented certain new and useful Improvements in Valves for Rotary Engines, of which the following is a specification.

This invention relates to rotary engines of 10 that class in which two cylinders on parallel shafts are geared together, the circumference of one cylinder being in contact with the other for the greater part of their revolution and in which one cylinder has a radial piston extending from it at one part of its circumference and the other (which forms a rotating abutment) has a recess in its circumference which allows the piston to pass as the cylinders revolve and in which also a cylindrical 15 casing surrounds the rotating cylinders, the piston on the one cylinder fitting to the interior of one portion of the casing and the remainder of the casing fitting around the cylindrical abutment. According to this invention 20 two such engines are formed together end to end. The cylinders which carry the pistons are upon one shaft, which extends through both. The cylindrical abutments are upon another shaft, which also extends through 25 both, and the piston of one division of the engine is set on the opposite side of the shaft to the piston of the other division, so that when one piston is passing the abutment which works with it the other has upon it a full pressure of steam.

For admitting steam to and allowing it to pass from the annular space around which the radial piston of each division travels two passages are formed, opening into the annular 30 space of that division on either side of and close to the abutment. The passages lead to a directing or reversing valve by which steam can be supplied to either passage, while the other is opened to the exhaust, according to 35 the direction in which the engine is to be driven. Steam is supplied to this directing valve through a second cylindrical valve, which is geared to and revolves with the other revolving shafts and is so formed as to cut off 40 the steam-supply to either division of the engine at the time when the radial piston of that division is passing the abutment which works

with it. One reversing-valve and one rotating cut-off valve serve for both divisions of the engine. The cut-off valve is cylindrical 55 and hollow. A portion of its circumference is exposed to steam in a steam space along one side of it. It has two opposite ports in its sides, one near each end. Steam passes to the interior of the valve through one of the 60 ports in its side and through the other port passes to one or other end of the directing or reversing valve, to be directed by it either to the channel leading to one side of the abutment or the other of one of the divisions. Similarly when the cut-off valve has made a half-turn steam is directed to the other division. The directing or reversing valve is also cylindrical and hollow with ports in its side and inclined partitions by which when the valve 65 is turned into one position steam is directed to one or other of the channels leading to the annular channels, while the other is opened to the exhaust. Similar cut-off and directing or reversing valves can be used with unduplicated single engines.

The above improvements are shown in the drawings annexed.

Figure 1 is a side elevation of the engine. Fig. 2 is a vertical transverse section through 80 one division of the engine. Fig. 3 is a horizontal section through the valves. Fig. 4 is a modification of the engine, in which the two valves are placed one above the other in place of side by side.

A A' are two cylinders on a shaft A². Each cylinder carries a radial piston A³, the piston carried by the cylinder A being on the opposite side of the shaft to the piston carried by the cylinder A'.

B B' are the cylindrical abutments on the shaft B².

C is a casing inclosing the piston-carrying cylinder and cylindrical abutment of each division of the engine.

D is the reversing-valve, and E the continuously-revolving valve for controlling the admission of steam first to one division of the engine and then to the other. The spindle of this valve and the shafts A² B² are all geared 100 together by gear-wheels F, so that they revolve at the same speed.

G G' are passages leading from opposite sides of the casing of the valve D to the in-

No. 654,228.

Patented July 24, 1900.

N. A. CHRISTENSEN.
VALVE GEAR FOR ENGINES.

(Application filed Nov. 21, 1898.)

(No Model.)

3 Sheets—Sheet 1.

1. The first step in the process of creating a new product is to identify the target market. This involves research into consumer needs, wants, and behaviors, as well as an analysis of the competitive landscape. The goal is to determine the specific needs of the target market and how the new product can best meet those needs.

2. Once the target market is identified, the next step is to develop a product concept. This involves creating a detailed description of the product, including its features, benefits, and unique selling proposition. The product concept should be designed to appeal to the specific needs of the target market.

3. The third step is to create a product prototype. This involves developing a physical or digital representation of the product, based on the product concept. The prototype should be tested and refined to ensure it meets the needs of the target market.

4. The fourth step is to develop a marketing plan. This involves identifying the most effective ways to promote the product to the target market, including advertising, public relations, and sales promotions. The marketing plan should be designed to create awareness of the product and encourage consumer purchase.

5. The fifth step is to launch the product. This involves introducing the product to the market through various channels, such as retail stores, online platforms, or direct sales. The launch should be carefully planned to ensure a smooth transition and maximum impact.

6. The final step is to monitor and evaluate the product's performance. This involves tracking sales data, consumer feedback, and market trends to determine the product's success. The product should be evaluated on a regular basis to ensure it remains competitive and meets consumer needs.
